UNITED STATES PATENT OFFICE.

JOHN H. GOSNELL, OF WHITEWRIGHT, TEXAS.

RADIATOR CAP.

Application filed April 30, 1921. Serial No. 465,781.

To all whom it may concern:

Be it known that I, JOHN H. GOSNELL, a citizen of the United States, residing at Whitewright, in the county of Grayson and State of Texas, have invented new and useful Improvements in Radiator Caps, of which the following is a specification.

This invention relates generally to caps or covers for radiators of motor vehicles, and is adapted particularly for use in connection with the filling opening, of radiators of tractors of that type wherein the filling opening is covered with a plate as distinguished from a screw top.

15 The primary object of the invention is to provide a cap or cover for the filling opening which facilitates filling of the radiator, minimizing the opportunity for waste of water in such operation, which prevents 20 splashing of the water from the radiator, which enables steam or vapors to escape when pressure within the radiator becomes excessive and yet which is so arranged as to promote condensation, thereby greatly economizing the water in the cooling system.

A further object of the invention is to 30 provide a cap of the character stated of simple and inexpensive construction, easy of installation, and which so affects the water of the cooling system as to maintain the latter at a low temperature, and which will prove thoroughly practical and efficient in use.

With these and other objects in view, the 35 invention consists of the features of construction, combination and arrangement of parts, hereinafter fully described and claimed, reference being had to the accompanying drawing, in which:

40 Figure 1 is a vertical sectional view taken through the radiator cap or cover of my invention and illustrating the manner in which the device is applied to a conventional type of radiator, and

45 Figure 2 is a vertical sectional view taken through the cap at right angles to the plane of Figure 1.

Referring now to the drawing 3 indicates the top portion of the radiator of the vehicle, 4 the filling opening therein surrounded by the upstanding flange 5 as usual, and 6 indicates the spaced parallel retaining bars within the radiator and to which the closure cap of the radiator is usually secured as by a spring, chain, cord or other suitable device.

In carrying out the invention a hollow body 7 is provided, the lower end of said body being open and of such size as to surround the opening 4 of the radiator. The 60 upper portion of the body 7 is provided with an inwardly and downwardly extending wall 8 constituting a funnel and baffle, the lower end of said wall being cut away as at 9 to provide a restricted opening. The upper edge of wall 8 engages the upper edges of body 7 and is permanently secured thereto. The upper end of body 7 is closed by a cap 10 hinged as at 11 to one side of the body and is adapted to be swung to open 70 or closed position, as will be understood. This cap or cover is provided with a number of openings 12 to permit steam to escape from the body 7.

The means for securing the body to the 75 radiator includes a bolt 13 having a T-head 14 at its lower end to engage with the lower edges of bars 6 in the radiator; the upper end of bolt 13 passing through a suitable opening disposed centrally of a cross member 15 secured to the inner walls of the funnel member 8. A nut 16 threaded upon the upper end of the said bolt enables the latter to be so adjusted that the body will be rigidly clamped down upon the upper surface 80 of the radiator. The lower edges of body 7 preferably seat upon a gasket 17 surrounding the filling opening 4, in order that a tight joint between the body and the filling opening is secured.

90 After applying the body to the radiator opening, the filling of the said radiator is readily facilitated, as the liquid may be poured very readily into the same through the funnel member 8. The cap 10 is moved 95 to closed position after the radiator is filled. As vapors and steam arise from the fluid within the radiator, they pass into the body 7, which, it will be observed, extends a considerable distance above the upper end of 100 the radiator and provides a relatively large radiating surface. By reason of the fact that the metal of which the body 7 is constructed is thin it is obvious that the same will cool rapidly, and vapors and steam entering the body will be subjected to a cooled atmosphere. The vapors and steam will therefore condense and flow back into the radiator. Such of the steam and vapors as condense upon the under surface of wall 8 110 will flow downwardly to the lower edge thereof and drop back into the radiator.

Excessive pressures within the radiator will be relieved by the steam passing upwardly through the opening 9 and out of the body through openings 12 in the closure thereof.

5 The invention in its preferred embodiment is adapted for use particularly with Fordson tractors, as their tractor is equipped with the spaced bars 6 to which the cover plate is usually secured. However, it is apparent that the body may be 10 equally as well used with tractors of other makes or types, and may, with slight variations in the details, be made adaptable to other types of radiators used upon tractors 15 or other motor vehicles.

Having thus fully described my invention, I claim:

1. The combination with a radiator casting having an opening therein and spaced bars within the radiator below said opening, 20 of a hollow metallic body disposed upon said casting and closing said opening, a funnel member disposed within said body, a bracket carried by said member, a bolt ad-

justably carried by said bracket and extending downwardly therethrough, a T-head on the lower end of said bolt adapted to engage with the bars of said radiator, and a foraminous cover upon the upper end of said body.

2. The combination with a radiator having an opening therein and spaced bars within the radiator below said opening; of a thin metallic body disposed upon said radiator and closing said opening, a gasket 35 surrounding said opening and supporting the lower edge of said body, a funnel member disposed within said body, a bracket carried by said member, a bolt adjustably carried by said bracket and extending 40 downwardly through said body, a T-head on the lower end of said bolt adapted to engage with the bars of said radiator, and a foraminous top hinged to the upper end of said body.

45 In testimony whereof I affix my signature.

JOHN H. GOSNELL.
